UNITED STATES PATENT OFFICE.

JACOB S. JAMMER, OF NEW YORK, N. Y., ASSIGNOR TO WESTERN ELECTRIC COMPANY, INCORPORATED, OF NEW YORK, N. Y., A CORPORATION OF NEW YORK.

CARRIER-WAVE SIGNALING SYSTEM.

Application filed December 29, 1920. Serial No. 493,749.

This invention relates to carrier wave signaling systems and more particularly to such systems wherein two-way operation is provided over two-way channels between an ordinary telephone line and a carrier wave transmission medium, such as the natural media used in radio communications, an ordinary telephone or telegraph transmission line, or a power transmission line. 5 In systems of this general type it is customary to have an ordinary low frequency telephone line normally connected to a two-way channel of a carrier wave terminal station. The low frequency line is connected 10 conjugately through a balanced transformer to the transmitting and receiving circuits of the two-way channel. For testing or other purposes, it is often necessary to disconnect the low frequency line from the carrier terminal channel, and for this purpose a jack or contact arrangement is inserted between 15 the balanced transformer and the low frequency line. With such an arrangement, unless some precaution is taken, the two-way channel will "sing" due to the unbalancing of the balanced transformer, when the low frequency line is disconnected. 20

It is an object of this invention to prevent the carrier channel from "singing" or otherwise mis-functioning due to this disconnection of the low frequency line. A feature of the invention is a jack and relay arrangement whereby this result may be accomplished. Another feature is the accomplishment of this result by short-circuiting the speech input circuit of the modulator. A further object is to provide an arrangement for short-circuiting the modulator which will function only when no substitute 35 line or equivalent apparatus is connected in place of the normally connected low frequency line.

In one embodiment of the invention these objects are accomplished by providing a relay, through a normally open contact of which the speech input circuit of a modulator may be short-circuited when desired. A low frequency line is terminated in a pair of jacks at the carrier terminal station. The low frequency terminal of the two-way carrier channel at the same station is also terminated in a pair of jacks. These two pairs of jacks are normally so connected together as to form a continuous transmission circuit between the low fre-

quency line and the two-way carrier channel. For call signaling the modulator short-circuiting relay is actuated. For other purposes, hereinafter to be described, this jack arrangement permits the operation of the 60 modulator short-circuiting relay, when a plug is inserted in the line jacks, providing the carrier terminal jacks are normal.

This invention will be more clearly understood from a detailed description of one 65 embodiment thereof and by reference to the accompanying drawing. The drawing illustrates a multiplex carrier telephone system showing in some detail one complete two-way carrier channel. Another similar 70 channel is merely indicated.

One terminal station only is shown, it being understood that there is a similar distant cooperating station (not shown). Two-way 75 channels of the station shown cooperate with corresponding two-way channels of the distant station. The transmitting circuit of one two-way channel in turn cooperates with the receiving circuit of the cooperating distant channel, and vice versa. 80

The terminal station illustrated in the drawing comprises a two-way carrier channel CH^1 . A transmitting circuit TC and a receiving circuit RC for channel CH^1 are connected to a common line ML through a balanced transformer 5. These circuits are also connected to a two-wire low frequency line 27 through a low frequency balanced transformer 4. Balanced transformers 4 and 5 have a high frequency net HFN and 85 a low frequency net LFN respectively connected to their line windings. The opposite terminals of the line windings of balanced transformer 4 are connected through the normally closed back contacts of ringing relay 6 to carrier terminal jacks 7, 7. A telephone station A is connected to a low frequency line L^1 , which terminates in a pair of jacks 8, 8. Jacks 7, 7 and 8, 8 are connected together by conductors 9, so that, 90 normally, a continuous transmission circuit extends from station A over line L^1 , through jacks 8, 8, conductors 9, jacks 7, 7, through channel CH^1 to the common line ML .

Transmitting circuit TC comprises a 105 source of carrier waves O , modulator M and modulator band filter MBF^1 . A speech input circuit for the modulator M comprises conductors 10 which are connected between the series winding of the balanced trans- 110

former 4 and the modulator M. The receiving circuit RC comprises a detector band filter DBF¹, a detector D, a detector amplifier DA, a speech frequency transformer 11, 5 and a low pass filter LPF connected to the bridge circuit of balanced transformer 4. For signaling purposes a signaling detector SD may be connected to the output circuit of the detector amplifier DA to provide 10 signaling energy for relay 12.

Modulator band filter MBF¹ and detector band filter DBF¹ are each adapted to pass a broad band of frequencies and may be of the general type described in Patents Nos. 15 1,227,113 and 1,227,114 to G. A. Campbell dated May 22, 1917. The constants of these filters are so chosen as to pass the particular range of frequencies, which are being used for the particular receiving or transmitting 20 circuit. In general the several receiving and transmitting circuits will employ distinctive bands of frequencies.

The low pass filter LPF is also of the general type described in the above mentioned 25 Campbell patents and is adapted to suppress currents having frequencies above the highest essential frequency of voice currents and to transmit with substantially negligible attenuation currents of the highest essential 30 voice frequency and of all lower frequencies.

The source of carrier waves O, the modulator M, the detector D, the detector amplifier DA and the signal detector SD may be of any suitable construction, but preferably 35 each is of the well-known three electrode thermionic vacuum tube type.

For transmitting call signals to a distant station, relays 13 and 14 are provided. For receiving call signals from a distant station, 40 signaling detector SD, relays 12, 6, and the lower winding of relay 3 are provided.

A second two-way channel, CH² is indicated, and as shown is also connected to the common line ML through the balanced transformer 5. On the low frequency side it terminates in a pair of jacks 15, 15. A second low frequency telephone terminal station B is associated through a low frequency line L² with a pair of jacks 16, 16 located 45 at the carrier terminal station. These jacks are likewise connected together to form a continuous circuit from telephone station B over low frequency line L², through jacks 50 16, 16, jacks 15, 15, two-way carrier channel 55 CH², and the balanced transformer 5 to the main line ML.

A modulator band filter MBF², and a detector band filter DBF², are connected respectively in the transmitting and receiving 60 circuits of two-way channel CH². These band filters are of the same general type as the corresponding filters in channel CH¹, differing only in their constants in order to provide selectivity between the several carrier channels. As shown, the modulator

band filters are connected in series with each other in a manner which is well known and described in United States Patent No. 1,428,155, September 5, 1922, issued to L. E. Espenschied and H. A. Affel, to form a 70 common transmitting circuit. Similarly the detector band filters are connected in series according to the same principle to form a common receiving circuit.

The block T represents a test set terminating in a pair of plugs 17, 17 which are adapted to connect with pairs of jacks as illustrated. Block TS may illustrate a telephone set adapted for use with either lines L¹ and L², or with two-way carrier channels 80 CH¹ and CH². Such telephone set may terminate in a pair of plugs 18, 18 similar to those previously described. A patching cord is also shown comprising the conductors 19 terminating at one end in a pair of plugs 20, 85 20 and at the other in a pair of plugs 21, 21. These pairs of plugs are likewise adapted to cooperate with the pairs of jacks as illustrated.

According to this invention, relay 3 at its 90 upper normally open back contact is adapted upon energization to short-circuit the speech input circuit 10 of the modulator by closing the circuit through conductors 22. Relay 3 may be energized by current in its upper 95 winding, a circuit for which may be traced from ground through battery 23, the upper winding of relay 3, normally closed upper contact of upper jack 7, conductor 24, normally open contact of upper jack 8 to 100 ground. Relay 3 may also be energized by current in its lower winding, a circuit for which may be traced from ground through battery 23, lower winding of relay 3, normally open back contact of relay 12 to ground. 105 This last traced circuit is provided to prevent "singing" in the two-way channel CH¹, while call signals are being received from a distant cooperating station.

The operation of the system under several 110 conditions will now be described.

The operation will first be described in connection with call signaling or ringing. With the connections as shown, it will be assumed that station A desires to call a distant cooperating station (not shown). The operator at station A will impress ringing current in a well-known manner on the line L¹, which will traverse line L¹, jacks 8, 8, conductors 9, jacks 7, 7, normally closed back contacts of relay 6, lower closed contact of relay 3, and windings of relay 13. Relay 13 will respond thereto by vibrating at the frequency of the ringing current, and cause the deenergization of relay 14 by opening its normally closed energizing circuit at the normally closed back contact of relay 13. The deenergization of relay 14 places a short-circuit upon the oscillator output circuit by closing a circuit to ground through its nor- 120 125 130

5 mally open front contact now closed. In the normal operation of the system, the oscillator O causes a continuous flow of carrier waves to the main line ML through the 10 modulator M, modulator band filter MBF¹, and balanced transformer 5. The short-circuiting of the oscillator O interrupts this normal flow of carrier waves as long as ringing current is impressed upon the low frequency line L¹.

15 The action at the cooperating distant station will now be described in connection with the receiving circuit RC of channel CH¹. Carrier waves transmitted from the distant 20 station, which are normally present on the common line ML are impressed upon the signaling detector SD from the balanced transformer 5, detector band filter DBF¹, detector D, and detector amplifier DA. The 25 signaling detector SD functions to cause a flow of unidirectional current in relay 12 to normally hold open its back contact. Carrier waves are prevented from being impressed upon the bridge circuit of balanced transformer 4 by means of the low pass filter LPF.

30 During the time when the train of carrier waves is interrupted at the distant transmitting station as just described, relay 12 is deenergized. Thereupon relays 3 and 6 are actuated by current from batteries 23 and 25 respectively, a circuit from ground through battery 23, lower winding of relay 3 and back contact of relay 12 (now closed) to ground being completed for relay 3 and 35 another circuit from ground, through battery 25, winding of relay 6, the same back contact of relay 12 (now closed) to ground for relay 6. Relay 3 which is quick acting places a short-circuit through conductors 22 40 upon the modulator input circuit 10 to prevent modulating current from entering the modulator therefrom. Relay 6, which is somewhat slower to act disconnects the low frequency terminal jacks 7, 7 from the 45 carrier channel CH¹, and connects a source of ringing current 26 to the low frequency conductors 27. Ringing current is therefore impressed upon the low frequency line L¹ to operate a signaling device (not shown) at 50 station A. When the low frequency conductors 27 are disconnected from the line windings of balanced transformer 4, carrier channel CH¹ is unbalanced at the transformer 4, and "singing" would result were 55 it not for the short-circuiting of the modulator input circuit 10. At the close of the ringing interval, carrier waves from the distant station are again impressed upon the signaling detector SD to energize the relay 12 which allows relays 6 and 3 to become deenergized, and the armatures to fall back to their normal positions. Relay 6 is 60 more quick to release than relay 3. It therefore connects the line L¹ to the carrier channel CH¹ before the short-circuit is removed

65 from the modulator input circuit 10, thereby guarding the circuit against false operation due to charging current in the line L¹ discharging through the modulator M and so into the carrier system as a whole. With 70 the circuit as shown, such discharge, if present, takes place through the short-circuiting conductors 22 and the energy thereof expends itself harmlessly in the resistance of 75 the circuit.

In another situation now to be explained, the carrier channel CH¹ is unbalanced and the modulator input circuit 10 is again short-circuited to prevent "singing" and misfunctioning of the system. Such a situation 80 arises when the low frequency line L¹ is disconnected from the carrier channel CH¹ by the insertion of plugs such as 17, 17 into jacks 8, 8 for testing purposes or the like.

85 When the plugs 17, 17 are inserted in the jacks 8, 8 the conductors 9 are disconnected from the line L¹ at the normally closed contacts of the jacks 8, 8. By the same operation a circuit through the upper winding of relay 3 is completed. This circuit extends 90 from ground, through battery 23, upper winding of relay 3, conductor 28, upper normally closed contact of upper jack 7, conductor 24, normally open contact of upper jack 8 (now closed) to ground. Relay 3, is 95 actuated, and a short-circuit as hereinbefore described is placed upon the modulator input circuit 10 to prevent "singing" due to the unbalancing of channel CH¹.

100 Still another situation may arise. While the line L¹ is being used for test purposes or the like, it may be desirable to connect another low frequency line such as L² to the carrier channel CH¹ whereby a subscriber at station B on line L² may communicate 105 over channel CH¹ and its cooperating distant channel. To permit of this, jacks 7, 7 and 16, 16 are connected together by a patching cord 19. Plugs 20, 20 are inserted into jacks 7, 7 and plugs 21, 21 are inserted into 110 jacks 16, 16. With plugs 17, 17 in jacks 8, 8 as hereinbefore described, channel CH¹ cannot function due to the short-circuit of the modulator input circuit 10. The insertion of plugs 20, 20 into jacks 7, 7, it will be 115 noted, removes this short-circuit by opening the energizing circuit of relay 3 through its upper winding at the upper normally closed contact (now open) of upper jack 7. Thus the carrier channel CH¹ is restored to normal, and it can function exactly the same 120 as though line L¹ were connected to it instead of line L².

125 It should be noted that the insertion of plugs 21, 21 in jacks 16, 16 will disable channel CH² by placing a short-circuit across the modulator input of that channel in the same manner as described in connection with channel CH¹ when plugs 17, 17 are inserted 130 in jacks 8, 8.

With the carrier terminal apparatus and low frequency lines in use as just described, carrier channel CH² may be restored to operating condition, by the insertion of plugs 18, 18 into jacks 15, 15. By this connection channel CH² may be used in connection with apparatus TS for talking purposes, testing purposes or the like.

Other combinations than those described 10 will be evident to those skilled in the art, but it will be noted that in every case, when the balance of a two-way channel is destroyed, deleterious effects such as singing are prevented by means independent of the 15 balance of the channel. It should also be noted that, while the channel is thus disabled, it may be restored to normal operating condition by the connection of suitable apparatus to the channel terminal jacks.

20 While the detailed description of the invention has been confined to its embodiment in a multiplex carrier wave signaling system, other embodiments thereof will be evident to those skilled in the art and the invention is to be limited only by the scope of the appended claims.

What is claimed is:

1. A common transmission line, a two-way communication circuit connected there- 30 to and having an incoming channel and an outgoing channel, a plurality of signaling circuits each adapted to be connected to said line over said communication circuit, and means for short-circuiting said outgoing 35 channel to prevent singing in the communication circuit when none of said signaling circuits are connected thereto.

2. A signal transmission circuit, a two-way communication channel connected there- 40 to and having an incoming and an outgoing channel, terminating means for said transmission circuit, a second transmission circuit, terminating means for said second transmission circuit, and means under the 45 control of both of said terminating means to disable said outgoing channel.

3. In a carrier wave signaling system, a two-way carrier channel, terminating means for said channel, a low frequency line, terminating means for said line, means to connect said two terminating means together to form a continuous transmission circuit, and means under the control of both said terminating means to disable said channel 55 for two-way communication.

4. In a signaling system, signal wave modifying means, a signal originating circuit, a contact arrangement connected to said signal wave modifying means, a second contact arrangement connected to said signal originating circuit, a connection between said contact arrangements to operably associate said signal wave modifying means with said signal originating circuit, means controlled by the operation of said second con-

tact arrangement to disable said signal wave modifying means, and means controlled by the operation of said first contact arrangement to prevent the disabling of the signal wave modifying means.

5. In a carrier wave signaling system, a two-way carrier channel, a pair of jacks for terminating said channel, a low frequency line, a pair of jacks for terminating said line, conductors connecting said line jacks and channel jacks together to form a continuous transmission circuit, and a relay under the control of both said line and channel terminating jacks to disable said channel for two-way communication.

6. In a signaling system, signal wave modifying means, a signal originating circuit, a pair of jacks connected to said wave modifying means, a second pair of jacks connected to said signal originating circuit, conductors connected to both of said pairs of jacks to operably associate said signal wave modifying means with said signal originating circuit, a pair of plugs, means controlled by the insertion of said plugs into the jacks connected to said signal originating circuit to disable said signal wave modifying means, a second pair of plugs, and means controlled by the insertion of said second pair of plugs into the jacks connected to said signal wave modifying means to prevent the disabling of the signal wave modifying means.

7. In a signaling system, a low frequency line, a two-way carrier channel comprising an outgoing and an incoming branch connected in conjugate relation with said line, means at a plurality of points for disconnecting said line from said channel, and means operated in conjunction with the operation of each of said disconnecting means 100 to disable said outgoing channel.

8. A combination in accordance with claim 7 in which one of said disconnecting means is adapted to disconnect the low frequency line from the carrier channel and to apply to 110 said line currents of signaling frequency.

9. A two-way communication system including a low frequency line, a two-way carrier channel comprising an outgoing and an incoming branch connected in conjugate relation with said line, said outgoing carrier branch including a source of carrier frequency waves and a modulator therefor, means located at a plurality of points in said line for disconnecting said line from said 115 carrier channel, a relay adapted to short circuit said modulator, and means for operating said relay in conjunction with the operation of any one of said disconnecting means.

In witness whereof, I hereunto subscribe my name this 24th day of December A. D., 1920.

JACOB S. JAMMER
